[57] CLAIM

The ornamental design for a combined diffusing dispenser and cap, as shown and described.

DESCRIPTION

FIG. 1 is a side elevational view of a combined diffusing dispenser and cap showing my new design;

FIG. 2 is a side elevational view shown with the cap removed for clarity of illustration;

FIG. 3 is a fragmentary perspective view thereof;

FIG. 4 is a top plan view thereof; and

FIG. 5 is a bottom plan view of the container assembly.

FIG. 1

FIG. 2

FIG. 3

FIG. 4

FIG. 5
